POSITION INDICATOR FOR STEERING WHEELS

Raymond H. Hill, North Wales, and Frank P. Kimball,
Souderton, Pa., assignors to Teleflex Incorporated,
North Wales, Pa., a corporation of Pennsylvania

Filed Jan. 27, 1964, Ser. No. 78,366

Term of patent 3½ years

(Cl. D52—6)

FIGURE 1 is a front elevational view of a position indicator for steering wheels showing our new design;

FIGURE 2 is a fragmentary enlarged front elevational view thereof; and

FIGURE 3 is a sectional view taken along the lines 3—3 of FIGURE 2.

The steering wheel shown in broken lines in FIGURE 1 and partly shown in FIGURES 2 and 3 is included for illustrative purposes only.

We claim:

The ornamental design for a position indicator for steering wheels, substantially as shown and described.
